MANIFOLDING MACHINE

Carl W. Brenn, Montclair, N. J., assignor to Auto-graphic Register Company, Hoboken, N. J., a corporation of New Jersey

Application September 28, 1935, Serial No. 42,623

7 Claims. (Cl. 282—3)

This invention relates to manifolding.

An object of this invention is to provide an improved means for locating and holding carbon sheets between the interleaved record sheets on the platen of the machine.

This means, in its preferred form, comprises a thin sheet metal bar clamped on the rear edge of a carbon sheet and adapted to otherwise hold and retain said sheet, and having a pair of apertures adapted to be slipped over hooks carried by the platen or other appropriate part of the machine.

The present invention relates to improvements in the carbon holding metal bar disclosed in my copending application Serial No. 719,133, filed April 5, 1934, now Patent No. 2,159,501, dated May 23, 1939, for improvements in Manifolding machines.

Other features and advantages will hereinafter appear.

In the accompanying drawing—

Figure 1 is a top view of the manifolding machine of the present invention, with the case and a record slip partly cut away to show the carbon paper and the clamping bar.

Fig. 2 is a side view of the machine partly in section on line 2-2 of Fig. 1.

Fig. 3 is an enlarged top view of a clamping bar attached to a carbon sheet, and shows one means employed to further grasp and retain the latter.

Fig. 4 is a sectional view on line 4-4 of Fig. 3.

Fig. 5 is a transverse sectional view of an open clamping bar of the type shown in Fig. 3, about 35 to receive and clamp a sheet of carbon paper.

Fig. 6 is an enlarged detail drawing of a modified form of the grasping and retaining means adapted to the metal clamping bar of the present invention.

40 Fig. 7 is a section taken on the line 7-7 of Fig. 6.

Fig. 8 is an enlarged detail view of another modified form of grasping and retaining means as adapted to the metal clamping bar of the present invention.

Fig. 9 is a section on line 9—9 of Fig. 8.

The present invention is herein illustrated as applied to a portable or hand-held type of manifolding machine, but it should be distinctly understood that the improvements may be applied to full-size or any other size or type of machine.

The machine illustrated is made of sheet metal blank and stamp having a bottom 10, sides 11, a front wall 12, and a rear wall 13 formed in one piece. A platen or writing bed 14 is pivotally

mounted in the upper portion of the machine. On the sides of the rearward or introductory portion of the platen, and integral with the same, are hooks 15 which project upwardly and vertically, and are directed backwardly.

In the machine of the present invention, the carbon paper 16 is provided with an inexpensive sheet metal bar 17, folded upon itself to clamp the rear margin of the carbon paper and otherwise adapted to hold it, and having ears 18 provided with elongated apertures 19 which are designed to be slipped over the hooks 15 of the platen. The bar 17 guides the record sheets 20 of the book or pile of sheets 21 over and under the rear edge of the carbon paper 16 and protects the latter 15 against being torn by protuberances on the sheets.

against being torn by protuberances on the sheet. In use, when the sheets 20 advance forwardly over the platen 14, the tendency is to drag the longitudinally extending carbon sheet forwardly with them. This forward force is transmitted to the bar 17 holding the carbon paper, and causes said bar to be securely retained in the jaws of the rearwardly directed hooks 15. However, the above action, which is desirable in retaining the bar 17 in the hooks 15, also tends to separate the carbon paper 16 from its holding bar 17.

In the present invention, means are provided whereby the carbon paper 16 is securely gripped in the metal holding bar 17 against separation. According to the present preferred form of the invention, a bar 17 (see Fig. 3) consisting of a flat metal strip folded on itself, clamps the margin of the carbon paper 16. The upper part or leaf of the bar 17 is provided with indentations, the under portions of which form inwardly directed protuberances 22 (see Figs. 3 and 5), which pierce the carbon paper 16, and which contact and press against the inner face 23 of the under leaf of the bar. Thus, the protuberances 22 act like pins or rivets through the bar and the carbon paper, and the effect is to securely hold the carbon paper in said metal bar and against separation therefrom. The above means for securing the carbon paper in the bar is particularly desirable, because it is effective and economical to practice, and because the only additional operation required is to first provide the blanked strip forming the bar 17 with indentations 22 before folding said strip over on itself to grasp the margin of the carbon paper 16. Fig. 4 shows a section of the carbon paper 16 and bar 17 taken on line 4-4 of Fig. 3, said bar being held in a hook 15 of the writing bed 13. The record sheets 20 are passing one above the bar 17 and the carbon 35 40 45 50

paper, and one below the bar and carbon paper.

A modified form of the holding bar 17 is shown in Fig. 6. The bar 17a is provided with apertures 24 in its under part or leaf, and with corresponding V-cuts 25 in its upper leaf.

The V-cuts are so located that when the blanked strip, which forms the bar 17a, is folded on itself and is clamping the carbon paper, said V-cuts are over the apertures 24. The tabs 26 formed by the V-cuts 25 may then be pushed through to pierce the paper, and may be folded back over the same, and occupy thereby the apertures 24 of the lower leaf of the bar 17. Thus the bar 17a will lie substantially flat with no outward protuberances, and yet will securely hold and retain the carbon paper 16a.

A second modification of the carbon paper holding bar of the present invention is shown in Figs. 8 and 9. In Fig. 8, V-shaped notches 27 are cut in the upper part or leaf of the bar 17b, and V-shaped tabs 28 are formed on the under leaf of said bar. After the blanked strip which forms the bar 17b has been folded on itself to clamp the carbon paper 16b, the tabs 28, (see Fig. 9) are bent upwardly to pierce said paper, and are folded back and against the latter, occupying thereby the notches 27 in said bar. The carbon paper 16b is thus held securely by the bar 17b, and said bar has no outward protuberances to undesirably augment its thickness or to catch or tear record sheets which pass over or under it.

The carbon holding metal bars, as disclosed by the present invention, provide for securely holding and retaining the carbon sheets in manifolding machines, and for guiding the record sheets of said machines over and under the rear edge of said carbon sheets, and for protecting the latter from being torn by the forward movement of said record sheets. Moreover, the means employed in the carbon holding bars of the present invention to pierce and otherwise secure the carbon sheets does not materially add to the thickness of said bars, and therefore does not cause undue bulkiness when several bars are employed, one on top of the other.

Variations and modifications may be made within the scope of this invention, and portions of the improvements may be used without others.

Having thus described the invention, I claim:

1. In a manifolding machine, a platen over which worksheets are advanced; means for supporting carbon sheets between the worksheets comprising transversely disposed bars; and hooks on the platen adapted to engage apertures in said bars, said hooks being directed rearwardly whereby the bars are maintained on the hooks by the drag imparted to the carbon sheets by the advancing worksheets.

2. In a manifolding machine, a platen over which worksheets are advanced; means for supporting carbon sheets between the worksheets comprising transversely disposed bars; and hooks on the platen adapted to engage apertures in said bars, said hooks being directed rearwardly whereby the bars are maintained on the hooks by the drag imparted to the carbon sheets by the advancing worksheets and said hooks being parts of plate-like elements extending in the direction of advance of the worksheets to engage the sides of the latter while said sheets are being advanced in proper interleaved relation with the carbon sheets.

3. The invention as defined in claim 1, in which said apertures are elongated transversely of the

bar, and there are mounting devices for said hooks having worksheet guiding surfaces extending in the direction of advance of the worksheets.

4. In a manifolding machine, a platen over which worksheets are advanced; and means for supporting carbon sheets between the worksheets comprising transversely disposed bars and hooks on the platen adapted to engage apertures in said bars, said hooks being directed rearwardly whereby the bars are maintained on the hooks by drag employed to the carbon sheets by the advancing worksheets, said bars each comprising a strip of thin material of greater length than the width of either the carbon sheet or the worksheet and being longitudinally folded on itself to provide two flat parallel leaves for engaging between them a marginal portion of the carbon sheet across the width thereof with said leaves so close together as to be separated merely by the thickness of the carbon sheet with one leaf having integral portions struck out therefrom and presenting piercing elements for the sheets and being of a height just sufficient to pierce the carbon sheet and nonpenetratingly press against the flat surfaces presented by the other leaf.

5. In a manifolding machine, a platen over which worksheets are advanced; and means for supporting carbon sheets between the worksheets comprising transversely disposed bars and hooks on the platen adapted to engage apertures in said bars, said hooks being directed rearwardly whereby the bars are maintained on the hooks by drag employed to the carbon sheets by the advancing worksheets, said bars each comprising a strip of thin material of greater length than the width of either the carbon sheet or the worksheet and being longitudinally folded on itself to provide two flat parallel leaves for engaging between them a marginal portion of the carbon sheet across the width thereof with said leaves so close together as to be separated merely by the thickness of the carbon sheet with one leaf having integral portions struck out therefrom and presenting arcuate cutting edges forming piercing elements for the sheets and being of a height just sufficient to pierce the carbon sheet and nonpenetratingly press against the flat surfaces presented by the other leaf.

6. In a manifolding machine, a platen over which worksheets are advanced; and means for supporting carbon sheets between the worksheets comprising transversely disposed bars and hooks on the platen adapted to engage apertures in said bars, said hooks being directed rearwardly whereby the bars are maintained on the hooks by drag employed to the carbon sheets by the advancing worksheets, said bars each comprising a strip of thin material of greater length than the width of either the carbon sheet or the worksheet and being longitudinally folded on itself to provide two flat parallel leaves for engaging between them a marginal portion of the carbon sheet across the width thereof with said leaves so close together as to be separated merely by the thickness of the carbon sheet with one leaf having integral portions struck out therefrom and presenting angularly arranged piercing elements for the sheets and being of a height just sufficient to pierce the carbon sheet and nonpenetratingly press against the flat surfaces presented by the other leaf.

7. In a manifolding machine, a platen over which worksheets are advanced; and means for supporting carbon sheets between the worksheets comprising transversely disposed bars and hooks

on the platen adapted to engage apertures in said bars, said hooks being directed rearwardly whereby the bars are maintained on the hooks by drag employed to the carbon sheets by the advancing worksheets, said bars each comprising a strip of thin material of greater length than the width of either the carbon sheet or the worksheet and being longitudinally folded on itself to provide two flat parallel leaves for engaging between them a marginal portion of the carbon sheet across the

width thereof with said leaves so close together as to be separated merely by the thickness of the carbon sheet with one leaf having integral portions struck out therefrom and presenting teats which are broken open at their tops to provide piercing elements for the sheets and being of a height just sufficient to pierce the carbon sheet and nonpenetratingly press against the flat surfaces presented by the other leaf. ⁵
